SIGNALING SYSTEM FOR RAILROADS

Ernest B. Kempster, Jr., Rochester, N. Y., assignor to General Railway Signal Company, Rochester, N. Y.

Application May 4, 1932, Serial No. 609,186

8 Claims. (Cl. 246—33)

This invention relates to a signaling system for railroads of the absolute-permissive-block type, and more particularly to the provision of means for safe-guarding traffic in spite of the 5 open condition of a track switch of an intermediate spur track, and also upon the entrance of a train into the single track section from such spur track.

In a railway signaling system of the absolute-permissive-block, or A. P. B. type, such for instance, as shown in the prior patent to S. N. Wight No. 1,294,736, granted February 18, 1919, stick relays are used to set up traffic in accordance with the direction in which a train is moving, the organization being such that traffic is absolutely blocked from moving in the opposite direction, and a stick relay at each signal is picked up by the passage of a train in the proper direction, and this stick relay permits the next 15 signal in the rear to indicate caution when the block just ahead of such stick relay is occupied. For example, in said patent, the pole changing of signal control relay, such as 58, removes plus energy from the signal clear wire and leaves it 20 only on the signal caution wire whereby to cause the signal to go to caution, as is well understood in this art. In accordance with present invention it is proposed to so interlock the two stick relays at the two signals approaching the spur 25 track, or turn out, that both of these stick relays may be controlled through the same line circuit, thereby economizing in line wire, and it is further proposed to include in this line circuit a switch box contact operated by the track switch 30 of such spur track, so that the two mentioned stick relays will be deenergized when the track switch is opened, and once deenergized they, or either of them, cannot be picked up except by the passage of a train in the proper direction, 35 providing of course, that the track switch has in the meantime been placed back into its normal main track position.

Other objects, purposes and characteristic features of the invention will in part be pointed out 45 hereinafter, and will in part be obvious from the accompanying drawing.

In describing the invention in detail reference will be made to the accompanying drawing, in which:

Fig. 1 shows conventionally one form of the present invention; and

Fig. 2 shows the split battery employed at each signal location having its midpoint connected to a common return wire C.

Referring to the drawing, the system shown

therein is a typical A. P. B system similar to the one illustrated in the Wight patent above mentioned, and in certain respects resembling the system shown in the application of Mersereau and Wells, Ser. No. 511,046 filed January 24, 1931, 5 now Patent No. 1,878,083, granted September 20, 1932.

In Fig. 1 of the drawing the track rails 5 of the main track have been shown divided into blocks by insulating joints 6, each block of which 10 includes a center-fed track circuit including the track battery 7 and the track relays T (having a suitable exponent), of which the track relays T¹, T², T³ and T⁴ only have been illustrated. At the entrance of each block, for each direction 15 of traffic there is provided a wayside signal, which for convenience has been illustrated as a semaphore signal, and of which the signals 2 and 4 have been illustrated for east-bound traffic, and the signals 1 and 3 have been illustrated for 20 west-bound traffic. Each of these signals is controlled by its associated home relay HD having a prefix corresponding to the number of the signal, and each home relay is controlled in accordance with the track relays in the block next in 25 advance, the pole changer relay PC (having a proper prefix) in advance and the stick relay S (having a proper prefix) in advance. At an intermediate point in the block shown, there is a spur track, or diverging route, including track 30 rails 8 and including a track switch 9, and this track switch has point detector contacts associated therewith, including contacts 10, 11 and 12 engaging suitable stationary contacts, conventionally illustrated by arrows. Two of these 35 contacts complete the two usual tumble-down circuits, this being accomplished by the contacts 10 and 11, and the contact 12 is included in the stick circuit for either of the stick relays 2S or 3S associated respectively with the signals 2 and 3. 40

Under normal clear traffic conditions all of the four signals 1, 2, 3 and 4 assume the clear position, under which condition the relay 2HD is energized through the following circuit:—beginning at the terminal (+) of a suitable battery, 45 such as the battery B shown in Fig. 2, front contact 15 of the pole changer relay 4PC, wire 16, front contact 17 of the track relay T³, wire 18, switch box contact 11, wire 19, front contact 20 of the track relay T², wire 21, winding of the 50 home relay 2HD, to the common return wire C connected to the midpoint of said battery. Similarly, the home relay 3HD is energized through the following circuit:—beginning at the terminal (+) of a suitable battery, front contact 25 of 55

the relay 1PC, wire 26, front contact 27 of track relay T², wire 28, switch box contact 10, wire 29, front contact 30 of the track relay T³, wire 31, winding of the relay 3HD, to the common return 5 wire C connected to the midpoint of said battery.

The pole changer relays, such as 1PC, 2PC, 3PC and 4PC are merely slow acting neutral repeater relays for the respective home relays having the same prefix, these relays being respectively 10 controlled through the contacts 33, 34, 35, and 36 of their respective associated home relays. These relays have been termed pole changer or PC relays, because the contacts of each of these relays determines whether the home relay of the 15 next signal in the rear shall be energized by current of positive or negative polarity. The directional stick relays 1S and 4S are controlled in the usual manner, for instance, as shown in the application of Mersereau and Wells, and these control 20 circuits are for convenience omitted. It is believed that the purpose and function of the stick relays 2S and 3S and their control circuits are most clearly understood by considering the operation of the system.

25

Operation

As illustrated, the stick relays 2S and 3S are normally deenergized. Let us assume that there is an east-bound train approaching the signal 2 30 in the direction governed by this signal. The presence of this approaching train, for reasons well understood by those skilled in the signalling art, causes deenergization of the home relay 1HD which results in deenergization of the relay 1PC, 35 which in turn deenergizes the home relay 3HD next in the rear, and drops contact 35 of relay 3HD, resulting in deenergization of the relay 3PC. The dropping of the relays 3HD and 3PC, places the stick relay 2S in condition for picking up, and 40 this relay 2S will pick up as soon as the east-bound train passes the signal 2.

Let us now assume that the east-bound train passes the signal 2, resulting in the dropping of the track relay T², due to the shunting action of the car wheels on the track circuit containing this track relay T², thereby closing the following energizing circuit for the stick relay 2S, as a result of the closure of the back contact 56 of the track relay T²:—beginning at the terminal (+) 45 of a suitable battery, back contact 40 of the stick relay 3S, wire 41, back contact 42 of the relay 3PC, wires 43 and 44, switch box or point detector contact 12, wires 54 and 53, front contact 52 of the track relay T², wire 55, back contact 56 of the track 50 relay T², wires 57 and 58, winding of the relay 2S, to the common return wire C. The closure of this pick-up circuit for the relay 2S causes this relay 2S to be energized and close its front contacts, as a result of which the following stick circuit is closed, it being understood that dropping of the track relay T² results in dropping of the home relay 2HD, which in turn after the expiration of a short period of time, since the relay 2PC 55 is slow acting, causes the relay 2PC to assume its deenergized position:—beginning at the terminal (+), back contact 40 of the stick relay 3S, wire 41, back contact 42 of the relay 3PC, wires 43 and 44, point detector contact 12, wires 54 and 60, back contact 61 of the relay 2HD, wire 62, front 60 stick contact 63 of the stick relay 2S, wires 64, 65 and 58, winding of the stick relay 2S, to the common return wire C. There is also an auxiliary stick circuit, which is the same as the stick circuit just traced up to and including the wire 54, 65 and from whence it continues through wire 53,

back contact 52 of the relay 2PC, wire 51, another stick contact 50 of the stick relay 2S, wires 66, 65 and 58, winding of the stick relay 2S to the common return wire C. The picking up of the stick relay 2S, through the medium of its front contact 61 and back contact 68 of the relay 2PC causes current of negative polarity to be applied to the next HD relay (not shown) in the rear.

Let us now assume that the east-bound train in 10 question, now moving from the signal 2 to the signal 4, advances to a point beyond the signal 4, as a result of which the stick relay 4S is picked up in any suitable and usual manner, as understood by those skilled in the art of A. P. B. signaling. The picking up of the stick relay 4S and the dropping of the pole changer relay 4PC in response to the passage of the train by the signal 4, causes the relay 2HD to be energized by current of negative polarity, as a result of which one of 20 the stick circuits for the stick relay 2S is broken at the back contact 61 of the relay 2HD, and the other stick circuit for the relay 2S is broken at the back contact 52 of the relay 2PC, so that the relay 2S is again deenergized. Also, shifting of 25 the polar armature of relay 2HD for example takes plus energy off of the signal clear control wire, to leave it on the signal caution control wire only, to thus put the signal 2 to caution.

In the same way as just explained a west-bound 30 train approaching the signal 3 will result in the deenergization of the home relay 4HD, which in turn will result in the deenergization of relay 2HD. Let us now assume that this west-bound train passes the signal 3 under which condition the 35 stick relay 3S will be picked up through the following pick-up circuit:—beginning at the terminal (+) of a suitable split battery, back contact 50 of the stick relay 2S, wire 51, back contact 52 of the relay 2PC, wires 53 and 54, switch 40 box contact 12, wires 44 and 43, front contact 42 of the relay 3PC, wire 45, back contact 46 of the track relay T³, wires 47 and 48, winding of the stick relay 3S to the common return wire C. With the relay 3S once picked up, it will be stuck 45 up through the following two stick circuits as soon as the relays 3HD and 3PC assume their de-energized position:—(1) beginning at the terminal (+), back contact 50 of the stick relay 2S, wire 51, back contact 52 of the relay 2PC, wires 53 and 54, contact 12, wires 44 and 70, back contact 71 of the relay 3HD, wire 72, stick contact 73 of the relay 3S, wires 74 and 48, winding of the relay 3S to the common return wire C; and (2) the same stick circuit up to and including the wire 44, wire 55 43, back contact 42 of the relay 3PC, wire 41, front stick contact 40 of the relay 3S, wires 16 and 48, winding of the relay 3S to the common return wire C. As soon as the west-bound train under 60 consideration passes the signal 1 next in advance, this relay 3HD will be energized by current of negative polarity, for reasons already explained, thereby resulting in the energization of the relay 3PC, and the opening of the two stick circuits just traced at the back contact 71 of the relay 3HD 65 and the back contact 42 of the relay 3PC.

It will be observed that the functioning of the system as thus far described is similar to the functioning of the usual absolute-permissive-block system, but that the structure is different 70 in that the pick-up and stick circuits of the two stick relays 2S and 3S include the same line wires 44—54, and include the same point detector contacts 12. The purpose of this departure from earlier systems results in the advantage of eliminating 75

nating one line wire, in that both of the stick relays 2S and 3S employ the same line wire, and at the same time the arrangement affords an interlock between the relays 2S and 3S that would otherwise not be present. This interlock exists because the relay 2S must be picked up through the back contact of the relay 3S and the relay 3S must be picked up through the back contact of the relay 2S. Also, the same point detector contact 12 serves to deenergize both of these stick relays 2S and 3S upon opening of the track switch 9. In other words, irrespective of whether the relay 2S, or whether the relay 3S is energized opening of the track switch 9 will deenergize such energized stick relay. If a stick relay has been thus deenergized by the opening of a track switch 9, such stick relay cannot again be picked up except by the passage of a train, so that irrespective of whether the train is coming from, or entering into the spur track 8, moves in an easterly direction or in a westerly direction, all of the signals governing traffic toward the spur track 8 will be put to stop, and the direction of travel is established by the train itself as it passes either the signal 1 or the signal 4.

Having thus shown and described only one particular embodiment of the present invention, it is desired to be understood that the particular system conventionally illustrating this invention has not been selected for the purpose of showing the exact construction preferably employed in practicing the invention nor has it been selected to illustrate the scope of the invention, but it has been merely selected to facilitate description of the underlying principles of the invention and one way of carrying out these principles, and it is further desired to be understood that additions, modifications and alterations may be made to adapt the invention to the particular problem encountered in practicing the same, all without departing from the spirit or scope of the invention except as demanded by the scope of the following claims.

What I claim as new is:—

1. In a single track signaling system of the absolute-permissive-block type, the combination with two signals for governing traffic in opposite directions, of a pole changing stick relay associated with each of said signals for when energized pole changing a control circuit for causing the next signal in the rear to indicate caution, and of a pick-up and a stick circuit for each of said stick relays including a back contact of the other of said stick relays.

2. In a single track signaling system of the absolute-permissive-block type, the combination with two signals for governing traffic in opposite directions, a stick relay associated with each of said signals for when energized causing the next signal in the rear, and governing traffic in the same direction, to indicate caution, a line wire extending from one of said two signals to the other, and a stick circuit for each of said stick relays including said line wire.

3. In a single track signaling system of the absolute-permissive-block type, the combination with two signals for governing traffic in opposite directions, a stick relay associated with each of said signals for when energized causing the next signal in the rear to indicate caution, a line wire extending from one of said two signals to the other, and a pick-up and a stick circuit for each of said stick relays including said line wire.

4. In a single track signaling system of the absolute-permissive-block type, in combination, with two signals for governing traffic in opposite directions, a stick relay associated with each of said signals, which stick relay, when energized, causes the next signal in the rear to indicate caution, a line wire extending from one of said two signals to the other, a stick circuit for each of said stick relays including said line wire, a track switch located between said signals, and a contact in said line wire closed only if said track switch assumes the main track position.

5. In a single track signaling system of the absolute-permissive-block type, in combination, with two signals for governing traffic in opposite directions, a stick relay associated with each of said signals, which stick relay, when energized, causes the next signal in the rear to indicate caution, a line wire extending from one of said two signals to the other, a stick circuit for each of said stick relays including said line wire, a track switch located between said signals, and a contact in said line wire closed only if said track switch assumes the main track position.

6. In a single track signaling system of the absolute-permissive-block type, in combination, with two signals for governing traffic in opposite directions, a stick relay associated with each of said signals for, when energized, causing the next signal in the rear to indicate caution, a line wire extending from one of said signals to the other of said signals, a pick-up and a stick circuit for each of said stick relays including said line wire, a track switch located between said signals, and a contact in said line wire closed only if said track switch assumes the main track position.

7. In a single track signaling system of the absolute-permissive-block type, in combination, with two signals for governing traffic in opposite directions, a stick relay associated with each of said signals, which stick relay, when energized, causes the next signal in the rear to indicate caution, a line wire extending from one of said signals to the other of said signals, a stick circuit for each of said stick relays including said line wire, a track switch located between said signals, a contact in said line wire closed only if said track switch assumes the main track position, and contacts closed only if said track switch assumes the main track position included in clearing circuits for said signals.

8. In a single track signaling system of the absolute-permissive-block type, in combination, with two signals for governing traffic in opposite directions, a stick relay associated with each of said signals for when energized causing the next signal in the rear to indicate caution, a line wire extending from one of said signals to the other of said signals, a stick circuit for each of said stick relays including said line wire, a track switch located between said signals, a contact in said line wire closed only if said track switch assumes the main track position, a control relay for each signal to control the same, each control relay being deenergized if the next control relay in advance is deenergized, and contacts closed only if said track switch assumes the main track position included in the circuits for the control relays for said two signals.
